[57] CLAIM

The ornamental eyewear front, as shown and described.

DESCRIPTION

FIG. 1 is a front elevational view of an eyewear front showing my new design;

FIG. 2 is a top plan view thereof;

FIG. 3 is a side elevational view thereof, the opposite side being a mirror image;

FIG. 4 is a front, perspective view thereof; and,

FIG. 5 is a rear, perspective view thereof.

The portion of the design appearing in broken lines is for environmental purposes only and forms no part of the claimed design.
